UNITED STATES PATENT OFFICE.

DARRELL FRANK DYKE, OF CHICAGO, ILLINOIS, ASSIGNEE TO THE SENG COMPANY, A CORPORATION OF ILLINOIS.

KITCHEN-CABINET.

1,200,821.

Specification of Letters Patent.

Patented Oct. 10, 1916.

Application filed December 24, 1915. Serial No. 68,566.

To all whom it may concern:

Be it known that I, DARRELL FRANK DYKE, a citizen of the United States, residing at Chicago, in the county of Cook and State of Illinois, have invented a new and useful Kitchen-Cabinet, of which the following is a specification.

This invention relates to improvements in kitchen-cabinets, and has particular reference to such cabinets in which the flour-receptacle is movably supported within a compartment of the cabinet.

The objects of the invention are to provide a convenient support for the flour-receptacle, whereby the latter may be easily raised and lowered, for the purpose of refilling, locked when in its lowered position, automatically released when desired, such being accomplished with a minimum amount of labor or exertion upon the part of the house-wife, who is aided by counterbalancing springs suitably arranged in connection with the fixtures constituting the support.

Other objects and advantages of the invention will hereinafter appear, and the novel features thereof will be particularly pointed out in the claims.

Referring to the drawing—Figure 1 is a vertical sectional view of the upper portion of a conventional form of kitchen-cabinet provided with my improvements, the flour-receptacle being shown elevated in full lines and lowered in dotted lines, the latter being the position it occupies when being refilled; and, Fig. 2 is a detail in elevation of one of the plates employed for carrying the fixture.

Similar numerals of reference indicate similar parts in both figures of the drawing.

The cabinet 1, is of the conventional type, the upper half being divided vertically to produce the compartment 2, in which is commonly located the flour-receptacle, and which the hereinafter described fixture is designed to support. To each of the side-walls of this compartment 2, near the bottom, is secured, by means of ordinary screws, a supporting-plate 3. As these plates are duplicates, a description of one will serve for both. The supporting-plate 3, below

its center and near its lower edge, is provided with a slightly elongated bearing-opening 4, and, in front and above the same, with a segmental-shaped guide-slot 5, the latter being formed concentric with the bottom or lower end of said bearing-opening. A little in advance of the guide-slot 5, and from a point between its ends, there is loosely suspended, from a stud 8, a gravity-latch or dog 9, the inner edge and lower end of which is provided with downwardly disposed inclined notches 10. By positioning the latch or dog 9 as indicated, the latter lies across the guide-slot 5. Between the slot 5 and bearing 4, heretofore mentioned, is located an inwardly projecting fulcrum-stud 7, and another stud 6, may project inwardly from the upper rear corner of the plate.

In each of the elongated bearing-openings 4, is located the bearing-trunnion 11, the same projecting laterally from near the lower ends of a pair of receptacle-supporting swinging arms 10. These two arms are so mounted with relation to their supports that when elevated they slightly incline to the rear and within the compartment 2. The arms may be and preferably are connected and braced by a transverse approximately U-shaped bridge 14, by means of which they are steadied in their movements and also caused to move in unison. To this bridge and near the ends, may be connected the upper ends of a pair of counterbalancing helical springs 15, the lower ends of such springs being connected to the studs 6, heretofore mentioned, or to some other convenient and fixed point. The upper ends of the arms are preferably each provided with an inclined slot 13, for the reception of opposite trunnions 17, located at the opposite sides of and projecting from the usual form of flour-receptacle or container 16, whereby, as will be obvious, the latter is supported pivotally by said arms. Each of the arms 10, carries an outwardly projecting headed guide-stud 18, the same being coincident with and riding and engaging in the adjacent guide-slot 5; and also has its front edge, near its lower end, provided with a half-round notch 19, located in annular aline-

ment with the stud 7 of the adjacent plate 3, and therefore, designed to be engaged thereby when the arm is in its lowered position.

Taking, for example, the parts in which they are shown in Fig. 1, when it is desired to refill the flour-receptacle or container, it is simply necessary to draw the same forward and down to the position shown in Fig. 1 (dotted lines). As the arms 10 and the container 16 swing outward and downward, it will be observed that the headed studs 18 of the arms travel in the opposite curved guideslots 5, and also ride over the notches 10^a formed in the gravity-latches 9. If the container and arms are released at any point of their travel, the studs 18 are immediately engaged by the adjacent notches of the latches or dogs, and thus the parts become locked against return as would otherwise be caused by the counterbalancing-springs 15. While the flour-receptacle or container is thus locked and held in its lowered position, it may be conveniently refilled in the usual manner. It now becomes necessary to unlock the parts and return the refilled container to its normal or elevated position within the compartment 2. This is accomplished in a most convenient and easy manner. If the container has not already been depressed to its lowest locked position, that is, to a point where the lowest notches 10^a of the gravity-latches or dogs are in engagement with the studs 18, or if it has, it matters not, the operation being the same, namely, a further depression will cause the arms 10 to fulcrum on the studs 7 of the plates, the rear or inner ends of the arms swinging upward and the studs or trunnions 11 thereof moving to the upper ends 40 of the elongated bearing-openings 4. This depression of the arms serves to withdraw the studs 18 thereof from engagement with the notches of the gravity-latches or dogs so that the latter are free to drop by gravity 45 to a vertical position, whereby their notches are no longer in position to engage the studs 18. The container is then swung upward and rearward, being assisted somewhat by the counterbalancing-springs, the backs of 50 the latches or dogs riding over the studs 18. When wholly elevated the container with its weight will be somewhat in rear of the vertical and rest against the rear wall of the compartment 2. When wholly elevated as 55 described, the gravity-latches or dogs will be released from the studs 18 and fall to their normal vertical positions. It will be observed that the fulcrum-studs 7 also act as stops for limiting the downward movement of the arms 10 and were it not for their presence, the receptacle, when refilled, would automatically lower the arms 10 and release them from the gravity-latches or dogs. In 60 fact, this would occur before any complete refilling or when the weight of the receptacle 65

and its contents became sufficient to counterbalance the strength of the springs 15. To avoid this, therefore, as well as to produce convenient fulcrums, it is desirable to use the studs 7 as described.

Having described my invention, what I claim, is:

1. The combination with a kitchen-cabinet, of opposite arms pivoted at their lower ends within the same, a flour-receptacle or container pivotally supported between the free ends of the arms, studs projecting from the arms between the free ends and pivots thereof, gravity-latches positioned pivotally on the cabinet at one side of and above the path traveled by the studs and terminating above the lowermost position capable of being assumed by the studs when said arms are lowered, said latches having downwardly inclined teeth adapted to be successively engaged by said studs, whereby said arms are locked during such engagement of the studs and latches, guides for the arms, and springs connected to the arms for normally elevating the same.

2. The combination with a kitchen-cabinet, of opposite arms pivoted at their lower ends within the same, a flour-receptacle or container pivotally supported between the free ends of the arms, headed studs projecting laterally from the arms, curved guides concentric with the pivots of the arms and engaging and interlocking with the studs, pivoted gravity-latches positioned above said guides and terminating above the lower ends of the same and provided with a series of inclined teeth adapted to be successively engaged by the studs of the arms, and return springs for normally elevating the arms.

3. The combination with a kitchen-cabinet, of opposite plates secured to the side-walls thereof, each plate being provided with an elongated bearing-opening, a fulcrum-stud in advance thereof, and a guide-slot in advance of the fulcrum-stud, opposite-arms having bearing trunnions located in the elongated bearing-openings and adapted to rest upon and be stopped by the fulcrum-studs, guide-studs extending from the arms and engaging the guide-slots, notched gravity-latches pivoted to the plates and lying in the paths of the guide-studs and adapted to engage the same, and retracting counterbalancing-springs connected to the arms.

4. The combination with a kitchen-cabinet, of opposite plates secured to the side-walls thereof, each plate being provided with an elongated bearing-opening, a fulcrum-stud concentric with and in advance thereof, and a curved guide-slot in advance of the fulcrum-stud and concentric with the bearing-opening, opposite arms having bearing-trunnions located in the elongated bearing-openings of the plates and provided with notches to receive the fulcrum-studs, guide-studs ex-

tending from the arms and engaging the guide-slots, notched gravity-latches pivoted to the plates at points above the guide-slots and overlying the same, a transverse bridge 5 connecting the arms, and springs connected to the same and to the plates.

5. The combination with a kitchen-cabinet, of opposite arms pivoted to rock therein, fulcrums arranged in advance of the pivots 10 of the arms and in the path thereof, whereby said arms will fulcrum thereon when they are lowered, a flour-receptacle pivotally supported between the free ends of the arms, a

latch for engaging the arms and locking the same in their lowered position and disengaging therefrom when said arms are rocked on their fulcrums, and springs for normally elevating the arms. 15

In testimony whereof, I have signed my name to this specification in the presence of 20 two subscribing witnesses.
